(57) **CLAIM**

The ornamental design for a slushie machine, as shown and described.

DESCRIPTION

FIG. 1 is a top perspective view of a slushie machine, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view of another embodiment;

FIG. 10 is a bottom and rear perspective view of another embodiment;

FIG. 11 is a front view of another embodiment;

FIG. 12 is a rear view of another embodiment;

FIG. 13 is a left side view of another embodiment;

FIG. 14 is a right side view of another embodiment;

FIG. 15 is a top view of another embodiment; and,

FIG. 16 is a bottom view of another embodiment.

The broken lines in the drawings illustrate portions of the slushie machine that form no part of the claimed design.
